(57) **ABSTRACT**

A container for a food product including a tamper-evident closure which forms an opening of a container. The closure comprises a sealing layer, adhesively sealed to the top of the container around the opening. The sealing layer is releasable from the container by pulling back on the sealing layer and resealable against the top layer to seal the opening when the sealing layer is moved back against the top. The tamper-evident feature comprises a portion of the top adjacent the opening and covered by the sealing layer, which extends from a position spaced from, and extends towards and terminates at the opening of the container. A portion of the tamper-evident feature falls into the container after the sealing layer has been pulled back for a first time to thereby indicate that the container has been previously opened.

TAMPER EVIDENT RESEALABLE CLOSURE**CROSS-REFERENCE TO RELATED APPLICATION**

This application is a divisional of U.S. application Ser. No. 11/438,705, filed May 23, 2006, which is incorporated herein by reference in its entirety.

FIELD OF THE INVENTION

The present invention relates generally to packages for storing articles and, more particularly, to a tamper-evident, resealable closure for such packages.

BACKGROUND OF THE INVENTION

Some containers for food products, such as cookies and other snacks, typically include a frame surrounded by an outer wrapper. The frame acts as a tray to hold the food product and to protect the food product from damage. One normally gains access to the contents of the container by opening one end of the wrapper, withdrawing the tray from inside thereof, and removing the food product from the tray. Reclosing the wrapper, once opened, generally includes folding or rolling the end down and clipping the end to keep the wrapper closed.

One recent advancement in the art of food containers includes a resealable container disclosed in U.S. Pat. No. 6,918,532 (hereinafter the "532 patent"), herein incorporated by reference. The '532 patent discloses a wrapper which forms a top of the container which has an access opening. A sealing layer is adhesively sealed to the top around the opening. The sealing layer is releasable from the container by pulling back on a tab and the sealing layer is resealable against the top layer to seal the opening when the sealing layer is moved back to a flat position on the top.

Other food products come packaged in plastic trays, such as thermoform trays which are sealed on the top using some type of lidding material. Several conventional lidding materials are available for covering conventional trays. Lidding materials may be metal foil, flexible plastic wrap or rigid plastic. One recent advancement in lidding materials for covering thermoform trays is provided in U.S. patent application Ser. No. 11/193,613 (herein incorporated by reference), which incorporates a resealable opening with a sealing layer similar to the one in the '532 patent.

In the packaging art, different methods have been used to indicate whether a package has been previously opened or whether the integrity of the package has been compromised. For example, in one prior dispensing bag for moistened tissues, shown in U.S. Pat. No. 6,428,867, tamper evidence is provided by a sealing label with an ink layer in the sealing area which leaves ink indicia in the sealing area to indicate that the package has been previously opened.

In another container, shown in U.S. patent application Ser. No. 11/029,651, herein incorporated by reference, various additional methods are shown to indicate whether a sealing layer has previously been removed from the container. One disclosed means for tamper-evident indication is the use of die-cut elongated strips running adjacent to the opening in the sealing area which is defined as the area around the opening of the container, under the sealing layer. One limitation with the use of the prior elongated strips is that the wrapper adjacent the elongated strips may become torn as the sealing layer is pulled back, thus compromising the integrity of the container's top.

There is a need in the art for a resealable container, preferably suitable for containing food items, which includes a new and improved tamper-evident indicator.

5 BRIEF SUMMARY OF THE INVENTION

The present invention generally relates to a resealable closure having a tamper-evident feature in the form of a flap or elongated strip which terminates at an opening covered by the 10 closure which falls into the container after the container has been opened for the first time.

The present invention, in one form, comprises a tamper-evident resealable closure comprising a first film layer, and a 15 first tear line and a second tear line formed in the first film layer. The first tear line defines a first panel section for providing an access opening through the film layer when separated from the first film layer along the first tear line. The second tear line runs from a position spaced from the first tear line to a position terminating at the first tear line and defining 20 a second panel section for indicating an initial opening of the closure when the second panel is separated from the first film layer along the second tear line. A second film layer is disposed on the first film layer and covers the first and second panel sections. The second film layer includes an adhesive 25 layer for resealably adhering a second film layer such that the first panel section is separated from the second film layer to expose the access opening and the second panel section is separated from the first and second film layers to provide a visual indication the closure has been opened after the second film layer has been removed from a first film layer.

In another form of the present invention, a tamper-evident closure comprises a wrapper forming a top of a container where the top has an access opening into the container. A sealing layer is adhesively sealed to the top around the opening. 35 The sealing layer is releasable from the top by pulling the sealing layer back in a peeling direction and reclosable against the top to seal the opening when the sealing layer is moved back against the top. A slit in the wrapper is located in the sealing area between the access opening and an adjacent edge of the container where the sealing layer is adhesively sealed to the top. The slit has a first end spaced from the opening and a second end terminating at the opening wherein the slit extends, in the peeling direction, from being spaced away from the opening to the opening.

40 In one further embodiment of the present invention, the slit forms an elongated strip. In an alternative further embodiment, the wrapper comprises a second slit adjacent to the first slit, extending from a position spaced from the opening and terminating at the opening, to form an elongated strip having one end spaced from the opening and a second end terminating at the opening.

The present invention, in another form thereof, concerns a 45 tamper-evident food container comprising a wrapper forming a container having a top where the top has an access opening so as to provide hand access to food contents of the container. A sealing layer is provided which is adhesively sealed to the top around the opening. The sealing layer is releasable when the sealing layer is pulled back in a peeling direction and reclosable against the top to seal the opening when the sealing layer is moved back against the top. A slit is provided in the 50 wrapper located in a sealing area between the access opening and the adjacent edge of the container where the sealing layer is adhesively sealed to the top. The slit has a first end spaced from the opening and a second end terminating at the opening wherein the slit extends in the peeling direction from being spaced away from the opening and terminating at the opening.

Other features and advantages of the present invention are stated in or apparent from detailed descriptions of presently preferred embodiments of the invention found hereinbelow.

BRIEF DESCRIPTION OF THE DRAWINGS

FIG. 1 is a perspective view of a package including an exemplary closure according to the present invention;

FIG. 2a is an enlarged plan view of the closure depicted in FIG. 1, showing the package prior to being opened for a first time;

FIG. 2b is the same closure of FIG. 2a, shown after the package has been opened and subsequently resealed in accordance with the present invention;

FIG. 3 is a cross-sectional view of the closure of FIG. 2a, taken along line 3-3;

FIG. 4 is a cross-sectional view of the closure of FIG. 3, depicting an initial opening of the closure;

FIG. 5 is a cross-sectional view of the closure of FIG. 3, depicting a resealed configuration of the closure after the initial opening;

FIG. 6 is an enlarged cross-sectional view of the closure of FIG. 2a, taken along line 6-6;

FIG. 7 is a cross-sectional view of the closure of FIG. 2b, taken along line 7-7;

FIG. 8 is a cross-sectional view of the closure of FIGS. 6 and 7, depicting a resealed condition of the closure;

FIG. 9 is a schematic showing the separation of the tamper-evident feature from the package of FIG. 1, in accordance with the present invention;

FIG. 10a is a plan view of a package including another closure, according to another aspect of the present invention, shown prior to opening the closure for a first time; and

FIG. 10b is the same closure depicted in FIG. 10a, shown after the closure has been previously opened and resealed.

DETAILED DESCRIPTION OF THE INVENTION

Referring now to the Figures, and in particular FIGS. 1-9, there is shown package 10 with closure 11 which incorporates a tamper-evident feature. Package 10 includes an outer wrapper which forms a first layer 12 of top 14, side 16 and crimped ends 18, 19. The first film layer 12 is formed from polymeric film or other flexible material that has been cut, folded or otherwise processed to define an interior space or receptacle for receiving the desired product, such as food items to be provided within a package 10. Package 10 can be used to store and distribute foodstuff, such as cookies, crackers, candy or other items. The film layer 12 may include graphics or other indicia to identify the contents of the package 10.

The closure 11 is formed directly on the first film layer 12 and includes a first tear line 20 formed into the first film layer 12. The first tear line 20 defines a first panel 22 that may be separate from the first film layer 12 along the tear line 20 to expose an opening 24 (FIG. 4) whereby access to the contents of the package 10 may be gained. Although the first tear line 20 is in the form of a full or complete rectilinear form, alternatively, tear line 20 may only include three sides, whereby first panel 22 is permanently attached to the first film layer 12 on one end and, thus, not cut on that one end.

Closure 11 further includes at least one second tear line 40 as a slit formed in the first film layer 12 adjacent to the first tear line 20. The second tear line 40 produces a second panel section 42 formed by the second tear line 40, which remains integrally joined to the first film layer 12 along end 44 of the panel 42 proximate the tab 30 end of the package 10. The second tear line 40 has a generally crescent shape extending

from a position spaced from the opening 24 defined by the first tear line 20, all the way to the first die cut 20. As a result, as viewed in the peeling direction 32, the second die cut 40 extends from a position spaced away from the first die cut 20 to the die cut 20.

The closure 11 includes a second film layer in the form of a sealing label such as sealing layer 26 disposed on the top 14 of the package 10 on the first film layer 12. The sealing layer 26 extends beyond the periphery of the first tear line 20 along a sealing area adjacent to the opening 24 to thereby cover the first panel section 22 and second panel 42.

This side of the second film layer 26, which faces the first film layer 12, is coated with an adhesive 28 (see FIGS. 3-5) so that the second film layer 26 may be releasably secured to the first film layer 12. The sealing layer 26 is provided with a tab 30 or other gripping feature which is not coated with adhesive 28 so that the sealing layer 26 may be peeled back from the first film layer 12 to open the package 10.

The sealing layer 26 may include a hinge portion 33, depicted in FIGS. 1, 2a and 2b as a series of undulating die cuts 34 formed through the sealing layer 26 along a peripheral edge positioned opposite the tab 30. As the sealing layer 26 is peeled back, the undulating die cuts 34 help to keep the edge of the sealing layer 26 adhesively secured to first film layer 12, while permitting the sealing layer 26 to be moved away from the access opening 24 to facilitate access to the contents of the package 10. While the hinge portion has been shown and described herein as comprising a series of undulating die cuts 34, it will be recognized that the hinge portion 33 may comprise a fold line defining a hinge or other arrangement suitable for hingedly coupling the sealing layer 26 to the first film layer 12.

As shown in FIGS. 3 and 4, the first panel section 22 is separated from the first film layer 12 along the first tear line 20 and remains adhered to the sealing layer 26 as the sealing layer 26 is peeled back in a peeling direction indicated by arrow 32 (FIGS. 1, 2 and 4) to open the package 10. After the contents of the package 10 have been accessed and it is desired to reseal the package 10, the sealing layer 26 may be reapplied to the first film layer 12, approximately in its original position, as depicted in FIG. 5. Because the sealing layer 26 extends beyond the periphery of the first panel section 22, the adhesive 26 disposed thereon facilitates resealing the package 10 with the first panel section 22 positioned over the access opening 24.

When the sealing layer 26 is peeled away from the first layer 12 to separate the first panel section 22 for a first time, a portion of the second panel section 42 is separated from the first film layer 12, but the integrally joined portion 44 of the second panel 42 ensures that the second panel 42 does not become completely separated from the first film layer 12. The second panel 42, therefore, remains attached to the first film layer 12 and eventually becomes separated from the adhesive 26 coated second film layer 26 as the second film layer 26 is peeled back for a first time in direction 32. Referring to the schematic of FIG. 9, as the sealing layer 26 is pulled back for a first time, the first tear line 20 tears successively, as indicated by the series of arrows 50, and the second tear line 40 tears successively as indicated by arrows 52 until the second tear line 40 terminates at the first tear line 20.

An advantage of having the second die cut extend and terminate at a first die cut is that any residual adhesive force which is applied to the respective second portions will be directed to the first die cut and, thus, the opening of the container, and not extend along the first layer to tear and/or potentially jeopardize the integrity of the package.

The material of the first layer **12** is formed such that the second panel section **42** moves in a direction away from the top **14** and inward of the package **10** when it becomes separated from the first film layer **12** and the sealing layer **26**, as depicted in FIGS. **2b**, **4** and **7**. Thereafter, the second panel section **42** provides a visual indication of an initial opening of the package **10** even when the sealing layer **26** is resealed against the first film layer **12** to reclose the package **10**. Specifically, the second panel section **42** remains joined to the first film layer **12** at end **44** while the remainder of the second panel **42** extends downwardly into the package **10**, as depicted in FIGS. **2b**, **4**, **5**, **7** and **8**, to create a void area **46** that is visually detectable when viewing the package **10**.

While FIGS. **1-8** show and describe an outer wrapper which forms a first layer **12** that covers the entire exterior of a package, the first layer **12** may form only a top surface of a package having a resealable opening, such as those packages disclosed in U.S. patent application Ser. No. 11/193,613, and thus closure **11** can form a closure over a thermoform tray having a first sealing layer as a lidding material over the top of the tray.

The first film layer **12** may be formed from polypropylene, polyethylene, cellophane, or any other polymeric material suitable for forming a package enclosure. Likewise, the sealing layer **26** may be formed from polypropylene, polyethylene or any other polymeric material suitable for forming a selectively releasable and resealable cover that can be adhered to the first film layer **12** as described above.

Referring now to FIGS. **10a** and **10b**, package **110** includes a closure **111** similar to that of package **10**. Package **110** differs from package **10** in that a third die cut **141** is formed in first sealing layer **112** which is parallel to second die cut **140** to thereby define a second panel **142** which is in the form of a generally elongated strip extending from a portion **144** spaced away from the first die cut **120** proximate the tab **130** and extending to the first die cut **120** as viewed in the peeling direction **132**. As with package **10**, one gains access into package **110** by pulling back on tab **130** which releases sealing layer **126** from the first layer **112** sealed to top **114**, which separates the first panel **122** from the first layer **112**, thereby exposing the opening (not shown). In addition, as the sealing layer **126** is pulled back in direction **132**, the second panel **142**

is separated from the first outer layer **114** on all sides except for the portion **144** which is permanently attached to the first outer layer **112**. As in the embodiment of FIGS. **1-9**, as shown in FIGS. **10a** and **10b**, the outer slit tears along a line that turns in and terminates at line **120**. In this embodiment, the inner slit **141** also turns in and terminates at line **120**. As a result, the second portion **142** separates from the adhesive of the sealing layer **126** and top **114**, and falls into the package **110**, as shown in FIG. **9b**.

It will now be apparent to one of ordinary skill in the art that the present tamper-evident features of the present closure offers benefits over prior tamper-evident features.

The invention claimed is:

1. A tamper-evident resealable closure, comprising:
a first film layer;
a first tear line formed into said first film layer and defining
a first panel section for providing an access opening
through said first film layer when separated from said
first film layer along said first tear line;
a second tear line formed into said first film layer, said
second tear line running from a position spaced from
said first tear line to a position terminating at said first
tear line, and defining a second panel section for indicating
an initial opening of the closure when the second
panel is separated from said first film layer along said
second tear line; and
a second film layer disposed on said first film layer and
covering said first and second panel sections, said sec-
ond film layer including an adhesive layer for releasably
adhering said second film layer to said first film layer
such that said first panel section is separated from said
first film layer to expose the access opening and said
second panel section is separated from said first and
second film layers to provide a visual indication the
closure has been opened after said second film layer has
been removed from said first film layer.

2. The tamper-evident resealable closure of claim **1**,
wherein said second film layer is transparent.

3. The tamper-evident closure of claim **1**, wherein said
second panel falls into said container when said second film
layer is peeled back for the first time.
